A. E. OSBORN.
INTERNAL COMBUSTION ENGINE.
APPLICATION FILED FEB. 25, 1920.

1,411,064.

Patented Mar. 28, 1922.

Inventor
Alden E. Osborn
By his Attorney
E. M. Marshall

UNITED STATES PATENT OFFICE.

ALDEN E. OSBORN, OF NEW YORK, N. Y.

INTERNAL-COMBUSTION ENGINE.

1,411,064.

Specification of Letters Patent. Patented Mar. 28, 1922.

Application filed February 25, 1920. Serial No. 361,294.

To all whom it may concern:

Be it known that I, ALDEN E. OSBORN, a citizen of the United States, and a resident of the city of New York, county and State 5 of New York, have invented certain new and useful Improvements in Internal-Combustion Engines, of which the following is a specification, reference being had to the accompanying drawing, forming a part 10 thereof.

My present invention relates particularly to engines of the type disclosed in my Patents 1,212,391 and 1,315,192 wherein the functions of the engine are controlled by a 15 reciprocating piston valve.

One of the general objects of my invention is to improve engines of this type and particularly to secure greater efficiency and added power.

20 An important feature of the invention is the provision of the piston valve which controls the functions of the engine with a valve, which may be of the poppet type and which will operate automatically as an auxiliary inlet for the gas.

Other features of the invention will appear as the specification proceeds.

In the drawing accompanying and forming a part of this specification, I have illustrated 30 the invention embodied in engines of the type disclosed in the two patents referred to, but would have it understood that the invention is not limited in its adaptation to these two particular engines, and further, 35 that various modifications may be made without departure from the spirit and scope of the invention as covered in the appended claims.

Figure 1 is a vertical sectional view of the 40 invention as incorporated in an engine of the single inlet port type disclosed in my Patent #1,212,391.

Figure 2 is a similar view of the invention as applied to an engine of the double inlet 45 port type disclosed in my Patent #1,315,192.

Figure 3 is a horizontal sectional view of the piston valve as taken on substantially the plane of line 3—3 of Figure 1.

In the illustrations, 5 designates the engine cylinder within which operates a piston 50 6 connected by a connecting rod 7 with the crank shaft 8.

In the first form shown, the cylinder is provided with a single intake port 9 located 55 near the end of the outward stroke of the

piston and controlled by a piston valve 10 reciprocating in a cylindrical valve seat 11 which is open at its upper end to the combustion chamber. This piston valve is of tubular construction, having an inlet port 12 in one side thereof to register with a supply passage 13 and having an outlet port 14 in the opposite side thereof to register with the cylinder port 9. The exhaust port 15 of the engine is controlled by the head 65 of the piston valve which is designed to traverse the same.

Mounted in the head of the piston valve is an automatic valve illustrated as a poppet valve 16, said valve being normally held to 70 its seat by a spring 17. This automatic valve I have shown as mounted in and carried by a valve cage 18 carrying a seat for the valve 16 and sleeved into the upper end of the tubular piston valve.

The poppet valve cage is shown detachably secured in its seat in the upper end of the piston valve by bolts 19 extending between the lugs 20 on the opposite inner side walls of the tubular piston valve and lugs 80 21 provided in the lower end of the valve cage. By this disposition of the securing bolts and lugs, the passage through the piston valve is not restricted to any appreciable extent and this arrangement also brings the 85 securing nuts 22 on the lower ends of the bolt rods 19 into position where they can be readily reached through the inlet port in the outer side of the piston valve.

The second form of the invention differs 90 from the one just described, principally in that the cylinder is provided with two intake ports 23 and 24 separated longitudinally, but both disposed toward the outer end of the piston stroke.

In the operation of the engines described, on the intake stroke of the piston the ports in the piston valve are brought into register with the cylinder ports and when the inside cylinder port is uncovered by the piston, the 100 charge is admitted to the cylinder above the piston. During the suction stroke and before the cylinder port or ports are opened by the piston, a partial vacuum is created in the cylinder which opens the poppet valve 105 and admits a supply of the intake gas directly into the head of the cylinder, such amount depending on the suction, the adjustment of the spring tension and other controlling factors. This action has the ef- 110

fect of relieving or partially relieving the vacuum, thereby taking some of the load off the piston and also produces a more complete charge in the cylinder.

5. What I claim is:

1. In an internal combustion engine, a tubular piston valve, a valve cage seated in the end of said piston valve, a poppet valve mounted in said valve cage, lugs on the opposite inner walls of the tubular piston valve and securing bolts extending between said lugs and the valve cage to removably secure said valve cage and the poppet valve mounted therein in place in the end of the piston valve.
10. In an internal combustion engine, a

cylinder having a seat for a piston valve open at one end to the interior of the cylinder, said cylinder having an intake port disposed toward the end of the outstroke of the piston, a piston valve operating in the piston seat and controlling the cylinder port, said piston valve being of tubular construction and having a passage extending up through the end thereof which is open to the inside 25 of the cylinder and a pressure controlled valve carried by the piston valve and governing said passage.

In witness whereof, I have hereunto set my hand this 20th day of February, 1920.

A. E. OSBORN.
